UNITED STATES PATENT OFFICE.

RICHARD S. CHEW, OF OAKLAND, CALIFORNIA.

CONCRETE FLOOR CONSTRUCTION.

1,054,338.

Specification of Letters Patent. Patented Feb. 25, 1913.

Application filed December 2, 1911. Serial No. 663,516.

To all whom it may concern:

Be it known that I, RICHARD S. CHEW, a citizen of the United States, residing at Oakland, in the county of Alameda and State of California, have invented new and useful 5 Improvements in Concrete Floor Construction, of which the following is a specification.

This invention relates to concrete floor 10 construction, and particularly pertains to a skeleton frame for concrete floors, roof, ceilings and the like.

It is the object of this invention to provide a skeleton frame for reinforcing and 15 supporting concrete floors and similar structures, which is designed to be embedded in the concrete to form an integral structure.

A further object is to provide a frame for 20 concrete floors and the like, in which the main reinforcing and supporting members are of short lengths and so arranged in relation to the girders as to act in conjunction with the concrete on the principle of cantilevers in supporting a concrete slab; and to 25 produce a floor in which the loads will be transmitted from the slab to the girders in substantially a radial direction.

Another object is to provide a frame for 30 reinforcing and supporting concrete slabs, which is simple in construction, economical, and which can be easily and quickly assembled.

Further objects of this invention, together 35 with the advantages derived by the use of same, will be made apparent in the following specification.

The invention consists of the parts and the construction and combination of parts as hereinafter more fully described and 40 claimed, having reference to the accompanying drawings, in which—

Figure 1 is a plan view of the skeleton frame, with parts broken away. Fig. 2 is a detail section on the line X—X, Fig. 1. 45 Fig. 3 is a detail section on the line Y—Y, Fig. 1.

In the drawings, A represents vertically disposed posts or columns of any suitable description, here shown as arranged at the 50 four corners of a rectangle, and B indicates horizontal girders extending between the columns A and secured thereto in any desired manner. The girders B are here shown as formed of I-beams, but any other 55 form may be employed.

The columns A and girders B are those

commonly employed in steel frame building construction, for supporting the outside walls, inside partitions, floors, etc.

The essence of this invention resides in 60 the manner of constructing and supporting a concrete floor on the girders B, which is accomplished by first placing diagonally arranged supporting beams 2 across the corners of the rectangle formed by the girders 65 B; the top of the beam 2 lying flush with the top of the girders B. When in position, the beams 2 and girders B form an octagonal, horizontally disposed frame, as shown in Fig. 1, across which is placed a light reinforcement, indicated at 3, which may consist of a wire netting or similar construction, the strands of which run at right angles to the girders B. The reinforcement 3 rests upon 70 the octagon frame and suspends therefrom in the shape of an approximate catenary 75 curve of revolution.

Mounted on the girders B and resting on the reinforcement 3 is a series of rods 4, or equivalents, which extend transverse of the 80 girders and are supported at their middle, so as to extend some distance on each side of the girders, as shown in Figs. 1 and 2. The rods 4 may be spaced at any suitable 85 distance apart and are arranged on the girders B between the ends of the diagonal beams 2.

A series of rods 5 are disposed upon the diagonal beams 2, at right angles thereto, with their ends projecting some distance 90 beyond the outer faces of the beams. The rods 5 are of such length that they will extend across the pair of parallel beams 2 on the opposite sides of the columns A; the two sets of rods 5 on the two pairs of beams 2 95 surrounding a column A, crossing each other at right angles, as shown in Fig. 1, and the ends of the outermost rods 5 in the series overlapping the outermost rods 4 on the girders B.

When the reinforcement 3 and the members 4—5 are positioned as just described, and as shown in Fig. 1, the concrete 6, or other plastic material of which the floor is to be formed, is molded thereon in any suitable manner, so as to embed the reinforcement 3 and the bars 4—5 therein; the girders B and the diagonal supports 2 being also incased in the concrete body. The upper surface of the slab thus formed is above 110 the bars 4—5 on the girder B and beams 2, while the bottom of the slab is a little be-

low the lowermost point of the catenated reinforcement 3.

From the foregoing it will be seen that the flat slab extending between the columns A 5 is carried on a practically circular support, as indicated by the dotted line *a* in Fig. 1. The slab thus virtually becomes a circular slab with its periphery supported and fixed on the girders B and the beams 2; the rods 10 4 and 5 in conjunction with concrete forming cantalivers, the outer ends of which extend into the periphery of the circular slab, thereby binding and fixing the slab in relation to its supports. By this arrangement 15 the loads imposed on the slab are transmitted to an annular support, thus permitting the slab to be constructed lighter and with less reinforcement than is possible with a rectangular support, as is now commonly 20 employed; analysis showing that a circular slab supported at its periphery is approximately 30% stronger than a rectangular slab of the same diameter supported on its four sides. By the arrangement of the bars 4—5, 25 here shown, short lengths of bars may be used, thus obviating the use of long rods extending from girder to girder in the form of beams. This arrangement also facilitates and cheapens construction, as it does not 30 require specially formed members nor skilled labor to place the several members in position.

A desirable feature of this invention is the facility with which the structure may be 35 analyzed, and the bearing capacity computed, a feature made possible by the cantaliver action of the reinforcing bars 4—5, and the circular support.

While I have described the members 4—5 40 as bars, it is manifest that wires, cables, mesh or analogous structures may be employed, if desired, and that the frame composed of the girders B may be of any desired outline other than rectangular; the essential 45 feature being to double the sides of a many-sided frame by the employment of diagonal members 2, so as to form the inner face of the frame as near on a circular or elliptical line as possible. It is also obvious that the 50 diagonal members 2 may be curved, if desired, so as to convert the frame from a four-sided figure into a circular or near circular figure.

Having thus described my invention, what 55 I claim and desire to secure by Letters Patent is—

1. A skeleton support for concrete floor construction, comprising a frame formed of horizontal girders arranged in rectangles 60 and beams extending diagonally across the

corners of the rectangles with their top surfaces substantially flush with the upper surfaces of the girders, and cantalivers supported on said beams and girders and extending at right-angles thereto, said cantalivers being formed of transverse rods resting on and projecting on each side of the beams and girders having their ends terminating a relatively short distance from the beams and girders, whereby a wide open space is 70 formed of approximately circular formation, and a plastic material embodying the girders, beams and cantalivers, and forming a slab which spans said space.

2. A skeleton support for concrete floor 75 construction, comprising a frame formed of horizontal girders arranged in rectangles and beams extending diagonally across the corners of the rectangles with their top surfaces substantially flush with the upper surfaces of the girders, cantalivers supported on said beams and girders and extending at right-angles thereto, and a catenated reinforcement extending across the frame beneath the cantalivers, said cantalivers being formed of transverse rods resting on and projecting on each side of the beams and girders, said rods having their ends terminating a relatively short distance from said beams and girders whereby a wide open 85 space is formed of approximately circular formation over which the catenated reinforcement extends.

3. A floor construction comprising the combination of a frame formed of horizontal 95 girders arranged in rectangles and beams extending diagonally across the corners of the rectangles with their top surfaces substantially flush with the upper surfaces of the girders, cantalivers supported on said beams 100 and girders and extending at right angles thereto, said cantalivers formed of spaced rods resting on and projecting on each side of the beams and girders and terminating a short distance therefrom, a catenated reinforcement extending across the frame beneath the cantalivers, and a plastic material embedding the girders, beams, cantalivers and the catenated reinforcement, said plastic material forming a slab which spans the 105 octagonal space between the ends of the cantalivers.

In testimony whereof I have hereunto set my hand in the presence of two subscribing witnesses.

RICHARD S. CHEW.
